UNITED STATES PATENT OFFICE.

CHARLES WILD, OF EUREKA, CALIFORNIA.

WELL-BORING MACHINE.

Application filed May 19, 1925. Serial No. 31,300.

This invention relates to a combined underreamer and digging apparatus, the primary object of the invention being to provide a device of this character that will 5 pump the material dislodged by the digging elements from the well, simultaneously with the digging action.

Another object of the invention is to provide digging blades so constructed that they 10 may be readily and easily removed or replaced when the same become damaged or otherwise rendered inoperative.

With the foregoing and other objects in view which will appear as the description 15 proceeds, the invention resides in the combination and arrangement of parts and in the details of construction hereinafter described and claimed, it being understood that changes in the precise embodiment of 20 the invention herein disclosed, may be made within the scope of what is claimed, without departing from the spirit of the invention.

Referring to the drawings:

Figure 1 is a longitudinal sectional view 25 through a combined underreamer and digger constructed in accordance with the invention.

Figure 2 is a plan view thereof.

Figure 3 is a transverse sectional view 30 taken on line 3—3 of Figure 1.

Figure 4 is an enlarged fragmental sectional view through the lower portion of the device.

Figure 5 is a fragmental sectional view 35 taken on line 5—5 of Figure 4.

Figure 6 is a fragmental sectional view 40 taken on line 6—6 of Figure 4.

Referring to the drawings in detail, the reference character 5 indicates the body portion 45 of the device which is cylindrical in formation, the same being provided with open ends.

Secured to the inner surface of the body portion 5 are bearing members 6 which are 50 arranged in suitable spaced relation with each other. Links 7 have their outer ends pivotally supported by the bearing members 6, the inner ends of the link members 7 having heads 8 formed thereon, which heads are 55 disposed between the disks 9 and 10 respectively secured at the lower end of the rod 11 there being provided a suitable spacing collar 12 between the disks 9 and 10 to hold the disks in proper spaced relation with each other.

In order that movement of the rod 11 will be limited a collar 11' is provided thereon, which collar is designed to engage the guiding disk 26 on the downward movement of 60 the rod, thereby insuring against the digging members passing too far beyond the bottom of the body portion 5.

Below the bearings 6 are guide members 13 that are formed with grooves 14 to accommodate the lateral flanges 15 formed on the wedge members 16' that act to lock the digging members including arms 16 within the guides 13. The upper ends of the arms 16 are bifurcated and are shown as having curved portions 17 defining hooks adapted to be 70 positioned over the pins 18 to secure the arms 16 to the link members 7. Secured to the arms 16 are plates 19 that are bolted to the arms as by means of the bolts 20, the plates being designed to overlie the pins 18 to secure the arms 16 in position. Thus it will be seen that due to this construction, the plates 19 may be readily and easily removed should it become necessary to remove 75 the arms 16 to sharpen the digging or cutting ends thereof, which cutting ends are indicated at 20.

Positioned within the body portion 5 and arranged in spaced relation to the lower end 80 thereof is a partitioning member 21 which is provided with a central opening to accommodate the spring housing 22, which is cylindrical in formation, the lower end of the housing 22 being secured to the partitioning member 21 by means of the nuts 23.

At the upper end of the spring housing 22 are threads to accommodate the union 24 which is provided for connecting the spring housing 22 to the tube 25. Secured within the housing 22 by means of the union 24 is a guiding disk 26 that is provided with a central opening to accommodate the rod 11, the upper end of the rod being threaded as at 27 to accommodate the stop 28.

Arranged within the housing 22 and bearing against the disk 26 is a coiled spring 29 which is designed to normally exert a downward pressure on the heads 8 for purposes to be hereinafter more fully described.

Formed in the partitioning member 21 are suitable openings that accommodate the pipes 30, the lower ends of the pipes terminating at points adjacent to the cutting ends 20 of the arms 16 while the upper ends 105 of these pipes are disposed above the parti-

tioning member 21 wherein they discharge the material drawn therethrough.

The reference character 31 indicates a movable hollow plunger which is provided with a plurality of vertical discharge pipes 32 that establish communication between the space above the partitioning member 21 and upper portion of the body portion 5.

Flap valves 33 are arranged in the pipes 32 and permit material to pass upwardly through the pipes 32 but prevent material from returning through these pipes.

A tubular member 34 forms the support for the plunger 31, the tubular member 34 being of a diameter to operate over the member 25, there being provided a packing gland 36 between the tubular member 34 and member 25 to insure a vacuum within the space between the partitioning member 21 and plunger 31, when the plunger 31 is moved upwardly.

At the upper end of the tubular member 34 are threads 37, which threads provide means for connecting the arm 38 to the tubular member 34, nuts 39 being provided on opposite sides of the arm 38 to secure the arm to the member 34. The outer end of the arm 38 operates between the guides 40 which are arranged within the body portion 5 as clearly illustrated by Figure 2 of the drawings, so that the arm 38 will be held against rotary movement within the body portion 5.

Secured to the arm 38 are spaced arms 41 that are provided with openings to accommodate the ends of the cross bar 42 which has an opening to accommodate the cable 43 by means of which the device may be operated to accomplish the purpose of the invention.

In order that material passing through the pipes 32 may be discharged from the body portion, openings 44 are provided in the body portion, which openings are arranged at a point approximately at the limit of the upward movement of the plunger 31 so that as material passes through the pipes 32, it may pass outwardly from the body portion 5.

The operation of the device is as follows: A cable is attached to the cross bar 42 and the device is held suspended, the weight of the body portion causing the hollow plunger 31 and tubular supporting member 34 to move upwardly until the upper end of the member 34 contacts with the stop 28, thereby directing a pull on the rod 11 and jaws of the cutting members to move them to their inactive positions, which results in the spring 29 being compressed.

The device is now lowered slowly into the well for the major portion of its travel until the device reaches for example four or five feet from the bottom of the well, where-

upon the device is dropped which brings the spring 29 into action forcing the cutting members to their expanded or active positions, the member 11 moving downwardly until the stop 28 contacts with the upper end of member 34.

With this downward movement, the valves 33 are opened, allowing material to pass upwardly through the plunger 31. Upon up pull directed to the member 31, the valves 33 will automatically close, producing a vacuum in the vacuum chamber arranged therebelow, which vacuum will follow through the device to the bottom of the well carrying with it sand or other loose material upwardly, depositing the material in the space between the members 31 and 21.

From the foregoing it will be seen that the present device will cut a circular recess in the ground surface leaving a central core, and the water and small particles of soil and stone will be drawn into the vacuum chamber.

After a recess of a certain depth has been formed, the device is removed and the vacuum chamber emptied of its contents, while the central core is being removed by an especially constructed tool.

It should also be understood that this tool is supported by the usual or well known rope or cable which is slightly twisted when the tool is dropped into the opening being formed, with the result that with each movement of the device, a slight rotary movement is imparted to change the location of the blades.

By this drill it is possible to cut a core which may be removed as before stated by an especially constructed tool forming the subject matter of another application to be filed, and the core preserved for sampling purposes.

I claim:—

1. In a device of the character described, a cylindrical body portion, a partition having openings, pipes extending through the openings and having their upper ends disposed above the partition arranged adjacent to one end of the body portion, said partition having a central opening, a rod extending through the opening, a tubular member housing the rod, a stop adjustably mounted on the upper end of the rod and adapted to be engaged by the tubular member, a plunger carried by the tubular member and adapted to move longitudinally of the body portion, said plunger adapted to draw material through the pipes to deposit material above the partitioning member, and digging members carried at the lower end of the rod.

2. In a device of the character described, a cylindrical body portion, a partitioning member supported within the body portion

- and having a plurality of openings formed therein, pipes extending through the openings, a rod supported within the body portion and having digging members arranged 5 at one end thereof, a plunger movable within the body portion, said plunger adapted to draw material through the pipes and means for connecting the rod and plunger to cause the rod and plunger to move simultaneously.
3. In a device of the character described, a body portion, a rod extending through the body portion, said rod having spaced disks at one end thereof, links pivotally connected 15 to the body portion and having heads disposed between the disks, digging members carried by the links, guides through which the digging members move, means for moving the rod, and means for sucking material 20 into the body portion.
4. In a device of the character described, a cylindrical body portion, a rod movable through the body portion, pivoted link members secured to the inner surface of the body 25 portion, digging members removably secured to the links, said rod adapted to operate to move the digging members, and means operating in the body portion for drawing material into the body portion.
5. In a device of the character described, a cylindrical body portion, a rod extending through the body portion, digging members pivotally supported at one end of the body portion, means controlled by the movement 35 of the rod for operating the digging members, means operating above the digging members for drawing material into the body portion simultaneously with the movement of the digging members in one direction.
6. In a device of the character described, a cylindrical body portion, a rod extending through the body portion, digging members, means connected with the digging members and rod for moving the digging members 45 downwardly and outwardly, one end of said rod being threaded, a stop member having a threaded opening mounted on the threaded portion of the rod, a plunger tube surrounding the rod and adapted to engage the stop 50 to move the rod longitudinally of the body portion, and a plunger operating in the body portion for drawing material through the body portion.
7. In a device of the character described, a cylindrical body portion, a partitioning member within the body portion and arranged adjacent to one end thereof, said partitioning member having lateral openings 55 and a central opening, a tube carrying a spring housing at the lower end thereof, positioned within the body portion, said spring housing having one end thereof disposed within the central opening of the partitioning member, a rod, disks on one end of the rod, a coiled spring within the spring 60 housing and engaging one of the disks to normally urge the rod downwardly, digging members supported by the body portion, links connected with the digging members, and having heads positioned between the 65 disks for moving the digging members, and means for drawing material through the lateral openings of the partitioning member.
8. In a device of the character described, a cylindrical body portion, a rod mounted 75 to operate longitudinally of the body portion, movable digging members supported within the body portion, links removably connected with the digging members, heads on the links, means on the rod for cooperating with the heads of the links for connecting the heads and rod, a coiled spring for normally urging the rod downwardly, and a plunger operating in the upper portion 80 of the body portion to draw material through 85 the body portion.
9. In a device of the character described, a rod supported within the body portion, means for moving the rod longitudinally of the body portion, digging members at the 90 lower end of the rod and adapted to move with the rod, a plunger operating above the digging members, pipes extending through the plunger and having flap valves, said plunger adapted to operate to draw material 95 through the body portion, and said body portion having discharge openings arranged above the plunger.

In testimony that I claim the foregoing as my own, I have hereto affixed my signature.

CHARLES WILD.
